(71) Applicant: **Da-Young Kim**, Daegu (KR)

Primary Examiner — T Chase Nelson

(72) Inventor: **Da-Young Kim**, Daegu (KR)

(74) *Attorney, Agent, or Firm* — Novick, Kim & Lee
PLLC; Jae Youn Kim

(**) Term: **15 Years**

(21) Appl. No.: **29/732,883**

CLAIM

(22) Filed: **Apr. 28, 2020**

I claim, the ornamental design for a storage container for contact lens, as shown and described.

Related U.S. Application Data

(63) Continuation-in-part of application No. 29/692,681, filed on May 28, 2019, now Pat. No. Des. 912,981.

FIG. 1 is a top perspective view of a storage container for contact lens, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom perspective view thereof;

FIG. 9 is a sectional view thereof taken along line 9-9 of FIG. 6;

FIG. 10 is a reference view thereof showing a configuration of use covered by a packing wrap;

FIG. 11 is a reference view thereof showing another configuration of use covered by a cap; and

FIG. 12 is a reference view of the storage container for contact lens with the covering shown in FIG. 10 and with the storage container placed on a storage case; and,

FIG. 13 is a reference view of the storage container for contact lens with the covering shown in FIG. 11 and with the storage container placed on a storage case.

The broken lines in the drawings show environmental structure and multiplied storage containers, none of which form a part of the claimed design.

1 Claim, 6 Drawing Sheets
